UNITED STATES PATENT OFFICE.

GEORGE EVANS WEBB, OF MILWAUKEE, WISCONSIN, ASSIGNOR TO KOEHRING COMPANY, OF MILWAUKEE, WISCONSIN, A CORPORATION.

SUBGRADE PLANER.

Original application filed January 6, 1922, Serial No. 527,423, and in Canada April 5, 1922. Divided and this application filed February 21, 1925. Serial No. 10,932.

This application is a division of my pending application, Serial No. 527,423, filed January 6, 1922, covering subgrade planer.

The invention embodies a subgrade dirt cutting and leveling machine, having special provisions for cutting work and for causing the dirt acted upon or removed to be leveled by certain scraping or leveling appliances.

The invention also involves certain combination means whereby a subgrade planer may be readily employed as an attachment to a portable road machine, as for instance, a concrete paver, and the two operated in conjunction with one another by the single power plant of the portable machine.

An understanding will be had of the detail construction of the planer and its mode of use in connection with a cooperating machine for propelling it, on reference to the following description, and accompanying drawings, in which latter the figures may be briefly described as follows:

Figure 1 is a fragmentary view of the rear end of a conventional type of a concrete paving machine, showing my subgrade finishing device cooperatively associated therewith.

Figure 2 is a top plan view of the subgrade finishing device, the endless tracks and front axle of a paving machine being shown in diagrammatic manner for the purpose of illustrating the manner of attaching the device of the invention to the paver.

Figure 3 is an enlarged transverse sectional view through the finishing device or earth planer.

Figure 4 is a rear view of the finishing device.

Figure 5 is an enlarged detail view of a portion of the forward scraper and the scarifying teeth which are associated therewith.

Describing my invention specifically, Figure 1 illustrates the subgrade planer arranged at the rear end of the paver, the latter only partly shown, and the distributing means is of the boom and bucket type, the boom being designated by the number 1^a and the bucket by the number 2^a. The multi-planes of the paver are designated 2, and the rear axle 2^b. The planer or finishing device as a unit is designated B and is adapted to be propelled by the paver A being shown as having a connection with the axle 2^b and

being located adjacent to the multiplanes 2. 55 In this position the subgrade finisher is located between the point occupied by the distributing bucket 2^a at its inner position on the boom, and the multiplanes 2 so that it does not interfere in any manner with the 60 movements of the bucket along the boom or prevent the mixed concrete batches from being deposited upon the subgrade at any point in the travel of the bucket along the boom.

The frame of this form of subgrade finisher includes spaced and substantially parallel transverse beams 21 and 22 which are connected at intervals in their length by the cross pieces 23. The ends of the frame are each provided with a pair of flanged rollers 70 24 which are adapted to travel upon the usual road rails or forms C. Horizontally disposed rollers 24^a are also shown as arranged at the ends of the frame for engagement with the road rails C to assist in holding the frame against lateral displacement.

A transversely extending scraper 25 is secured to the cross pieces 23 at a point somewhat to the rear of the front transverse beam 21, and a channel bar 25^a is shown as associated with the horizontally disposed and rearwardly extending upper edge portion of the scraper to stiffen and reinforce the same. This scraper 25 extends downwardly so as to engage the surface of the subgrade and is 80 forwardly inclined so that it can act effectively upon any elevations of the subgrade to plane or cut the same away. Associated with the front scraper 25 is a series of teeth 26, said teeth being shown as secured thereto 85 and extending downwardly along the front thereof. The purpose of these teeth is to assist in breaking up or rooting up the hard spots in the surface of the subgrade so that the device will operate effectively to remove 90 any high places in the subgrade. The loosened earth may be deposited in low places so as to fill the same, or, if it accumulates in sufficient quantities in front of the scraper 25 it will press over the top edge of 100 the scraper and drop upon the subgrade at the rear of the scraper. The space between the front scraper 25 and the front beam 21 is sufficient to permit of this passage of the loosened earth over the top of the front scraper in the manner indicated.

The rear beam 22 of the frame is provided with a rear scraper 27 which is shown as

disposed in a substantially vertical position. This scraper projects downwardly into engagement with the surface of the subgrade and cooperates with the front scraper to 5 smooth out the uneven places. Any raised points which may not have been all removed by the front scraper will be planed away by the rear scraper and the loose earth accumulating in front of the rear scraper will 10 be deposited in the low places so as to fill in the same. If an excessive quantity of loose earth should accumulate in front of the rear scraper, it would pass over the same, in which event it would have to be manually 15 removed from the subgrade, although this is a contingency which would not ordinarily happen if the preliminary work of grading had been properly done. Under some conditions it might be necessary for a workman 20 to shovel some loose earth between the two scrapers in order to provide sufficient material for filling in the depressions.

The connection between the subgrade finisher and the paving machine is such that 25 it is possible to alter the relative position of the two devices and position the paving machine at either side of the center of the road, as may be necessary to obtain the most effective results. A yoke member 28 is slidably associated with the axle 2^b of the traction devices 2 of the paver and carries a wheel 29 which is adapted to travel back and forth upon the axle in much the manner of a trolley. The yoke 28 is connected 30 by a pair of rearwardly diverging draw bars 30 to the frame of the subgrade finisher. The connection is such that the finisher is pulled along after the paver and propelled thereby, although the paver can be shifted 35 laterally with respect to the finishing machine and positioned upon one side of the road or the other side, as may be desired. The subgrade is finished and smoothed after the paver has passed over the same so that 40 it is put in proper condition to receive the concrete just before the concrete is deposited thereon, and this is accomplished without interfering in any manner with the functioning of any part of the paver.

45 As is indicated more clearly by Figure 2, both the front and rear scrapers may be formed so that they can be adjusted for different contours or configurations of the subgrade surface. As indicated, the rear scraper 50 27 is shown as formed in a plurality of sections which are adjustably secured to the rear beam 22 by fastening elements 31. By properly adjusting the scraper sections, the scrapers can be positioned at different elevations and also set for the desired contour of the subgrade surface.

Having thus described my invention, what I claim as new and desire to secure by Letters Patent, is:

55 1. A subgrade finishing device including

a frame, traction members at the ends of the frame adapted to travel on the usual road rails, and a pair of transversely extending scraper elements carried by the frame, the forward scraper element being inclined and 70 arranged so that loose earth will pass over the same and be deposited in the space between the two scrapers.

2. A subgrade finishing device including 75 a frame formed of transverse beams connected by cross pieces, traction means for supporting the frame on the road rails, and a scraper carried by the cross pieces in a spaced relation to the beams so that loosened soil can pass over the upper edge of the 80 scrapers.

3. A subgrade finishing device including 85 a frame formed of transverse beams connected by cross pieces, a scraper secured to the cross pieces at a point spaced from and adjacent to the forward beam so that dirt can pass upwardly over the scraper, and a second scraper secured to the rear beam.

4. A subgrade finishing device including 90 a frame formed with spaced transverse beams connected by cross bars, a scraper secured to the cross bars at a point spaced from and adjacent to the front beam, said scraper being inclined so that dirt will pass upwardly over the same, scarifying teeth arranged adjacent to the said scraper in cooperative relation thereto, and a second scraper secured to the rear beam.

5. A subgrade finishing device including a 100 frame formed of a pair of transverse beams connected by cross pieces, traction members at the ends of the frames adapted to travel upon the usual road rails, a front scraper secured to the cross pieces in a spaced relation to the front beam so that dirt can pass upwardly between the scraper and front beam and fall over the upper edge of the scraper, scarifying teeth associated with the front scraper, and a rear scraper secured to the rear beam.

6. In combination with a traction device 105 which includes an axle, of a subgrade finishing device mounted to travel upon the road rails, a trolley member movable back and forth upon the axle of the paver, and draft means between the trolley member and the subgrade finisher whereby the latter is connected to the paver in a trailing relation.

7. A subgrade finishing device including a 115 frame mounted to travel over the subgrade, and a pair of spaced scraping elements carried by the frame and arranged in a position transverse to the direction of movement thereof whereby materials accumulating between the scrapers will be deposited in the hollows or depressions of the road bed.

8. A subgrade finishing device including a 120 frame mounted to travel over the subgrade, a pair of spaced scraping elements carried by the frame and the rear scraping element 125 130

being arranged in a position transverse to the direction of movement of the frame, and scarifying teeth associated with the forward scraping element whereby elevations will be 5 cut away by the forward scraper and the loose material deposited in the hollows by the rear scraper.

9. A subgrade finishing machine including a frame mounted to travel over the subgrade, 10 a pair of spaced scraping elements carried by the frame and arranged in a position transverse to the direction of movement thereof, the forward scraper being inclined so that loose material will pass over the same 15 and accumulate in the space between the scraping elements where it will be deposited

in the hollows by the rear scraping elements.

10. A subgrade finishing machine including a frame to travel over the subgrade, a pair of spaced scraping elements carried by 20 the frame and arranged in a position transverse to the direction of movement thereof, the forward scraper being inclined so that loose material will pass over the same and accumulate in the space between the scraping 25 elements where it will be deposited in the hollows by the rear scraping elements, and scarifying means associated with the front scraper.

In testimony whereof I affix my signature.

GEORGE EVANS WEBB.
